UNITED STATES PATENT OFFICE.

ALBERT WAGSTAFF, OF FRANKFORT, NEW YORK, ASSIGNOR TO INTERNATIONAL HEATER COMPANY, OF UTICA, NEW YORK, A CORPORATION.

WARM-AIR-FURNACE RADIATOR.

Application filed April 27, 1925. Serial No. 26,096.

My present invention relates to a two piece radiator for a warm air furnace.

At one time the radiators for warm air furnaces were commonly formed of two sections 5 separately cast from separate patterns with the sections thereafter brought together to make a complete radiator including a central hollow dome and a ring spaced thereabouts with a flue connecting the dome and the ring. 10 The common defect in that construction was that the joint between the two sections did not remain permanently gas tight under the severe conditions to which such an article is subjected. To avoid that disadvantage complete radiators have been made in one piece 15 or from one casting. The disadvantages of this process are that it is much more difficult and costly to make the radiator in one casting; that such a casting has to be done entirely by hand instead of very largely by machine as in the case of the open sections of a two-piece radiator and that the spoilage or wastage in making complete radiators from one casting is proportionately much greater than 20 in the case of the two-piece radiators.

It is the purpose of my invention to provide a two-piece radiator having the two sections of such form, construction and co-operation that they may be very readily assembled to make a permanent gas tight joint 25 and so obtain the advantages of efficient, economical and rapid machine manufacture incident to the casting of open sections and yet have the advantage of a gas tight joint 30 heretofore incident only to a one piece radiator.

A further purpose is to provide a two-piece radiator having its sections of such form and relation that the two sections are exactly similar except that the top section will have a cap 35 over the dome while the section that is to be the bottom section will have its cavity open at the bottom to fit the top of the combustion chamber section of the furnace. 40 Through such close similarity in the form and construction of the two sections, I am enabled to make the castings for the two sections from the same main pattern, thus effecting a great saving in the cost of necessary 45 patterns for different sizes and types of furnaces besides the incidental advantage of having to store or handle half as many patterns as would ordinarily be done.

A further purpose is to form a two-piece

radiator for a furnace with the sections having their meeting edges especially adapted to form or facilitate the forming of a gas tight and good mechanical joint at all parts of the meeting edges of the two sections, and still further to have all parts of the meeting edges 55 of the two sections provided with two spaced flanges of unequal height so as to form a broken joint when the sections are placed together and furthermore to have the opposite halves or other equal fractional parts of the 60 sections for these dissimilar flanges reversely arranged so that two sections cast from the same main pattern may be brought together to form a gas-tight and broken joint effect at 65 all meeting edges of the two sections. 70

Further purposes and advantages of my invention will appear in the specification and claims herein.

Fig. 1 is a side elevation of a two-piece radiator embodying my invention as completely assembled and in place upon the top 75 of a combustion chamber section of a furnace.

Fig. 2 is a top view of a bottom section formed pursuant to my invention. 80

Fig. 3 is a transverse sectional view of the bottom section on line 3—3 of Fig. 2.

Fig. 4 is a similar sectional view through the top section.

Fig. 5 is a transverse vertical sectional view 85 through the said top and bottom sections, with said sections in opposing position but spaced slightly from each other.

Fig. 6 is a similar sectional view of said parts when assembled. 90

Referring to the drawings in a more particular description, it will be said that I have illustrated my invention in radiators for furnaces in connection with the common type of such radiators where the complete radiator 95 comprises a central hollow dome 10 and a hollow ring 11 spaced therefrom and communicating therewith through a hollow flue 12. From the ring 11 there projects outwardly the smoke passage 13 adapted to receive the usual smoke pipe (not shown), this passage 13 usually and preferably being located at the portion of the ring farthest away from the connecting flue 12. From the ring 11 there also extends outwardly the usual 100 clean out passage 14, such passage being usually located as shown in the drawings directly across from the flue 12. The parts of the

dome and ring remote from the strong connecting flue 12 are connected by bracing webs 33.

A radiator of this general type is formed pursuant to my invention from two almost identical sections, namely: a bottom section 16 and a top section 17; the respective sections comprising the bottom and top half of the complete radiator are divided upon a central horizontal plane. Each section therefore provides an annular portion 18 U-shaped in cross section and a central cup shaped portion 19 with these parts connected by a portion 20 U-shaped in cross section. These sections are exactly similar in construction, shape, size and arrangement except that the top section 17 has its central portion 19 closed away from its joint edges by a cap 21, which is at the top of the section when cast but at the bottom of the section as shown in Fig. 4; but which cap becomes the top of the dome when said upper section is turned over to form the top of a radiator as shown in Figs. 5 and 6.

It will be understood that when the bottom section 17 is placed on top of a lower section 16, the U-shaped portions 18 will unite to form the ring 11 and the straight U-shaped portions 20 will unite to form the complete flue 12 and that the central portions 19 will unite to form the dome 10 covered at its top by the cap 21 and open at its bottom to rest upon and communicate with the feed section 22 of the furnace.

The meeting edges of the bottom section 17 and top section 18 throughout the dome 10, ring 11 and flue 12 clean out opening 14 and smoke passages 13 are thickened or widened as shown in a somewhat exaggerated form in the drawings and each edge is provided with two spaced flanges, one the high flange 23 and one the low flange 24, with a groove 25 therebetween. The arrangement is such that when the top and bottom section are properly assembled, the high flanges upon one section will come opposite the low flanges on the other section and the low flanges upon the first section will come opposite the high flanges upon the second section resulting as shown particularly in Fig. 6 in obtaining what is commonly called a broken joint with the two grooves 25 uniting into one cavity which is filled prior to the assembling of the parts with a packing 34 usually provided in the form of an asbestos wick or cord supplemented with asbestos cement.

In order however, to produce this result with sections cast from the same main pattern, it will be obvious that the meeting edges have to be specially formed and particularly cannot have the high and low flanges extend continuously all around the section edges that are to form the ring and the dome and even the flue of the radiator. I accomplish the desired result however, by having the opposite halves (or other equal fractional parts)

of each section have its high and low flanges reversely arranged. In the drawings I have shown as a convenient and the preferred construction the reversal of these flanges in the opposite halves of each section. That is the high and low flanges are arranged in one relative position upon the left hand half of the castings as shown in Figs. 2, 3 and 4 while the flanges upon the right hand half are arranged in exactly the reverse order. 75

In other words, the high flange 23 for the outer wall of the radiator ring 11 on the left hand part of the casting is outside of the groove 25, that is farther from the center of the casting while on the right hand part of the ring this wall has its high flange inside of the groove 25. A similar reversal of the arrangement of the flanges is seen also on the inner wall of this ring in that the left hand half of the casting has its high flange inside of the groove that is towards the center of the casting from the groove while the corresponding right hand portion of the casting has its high flange outside of the groove. Similarly, the two halves of the upper edges or adjoining edges of the dome 10 and of the flue 12 have the high flange outside the groove on the left hand half and inside of the groove on the right hand half. This construction it will be seen results in the formation of a shoulder 27 facing to the left directly at the back of the inner wall of the ring 11 where the high flange 23 coming from the right outside of the groove 25 steps down to the low flange 24, coming from the left. To the inner side of the groove there is another shoulder 28 facing to the right made by the high flange 23 upon the left hand of the casting stepping down to meet the low flange 24 upon the right hand half of the casting. At the back of the dome a shoulder 29 faces to the right beyond the groove and a shoulder 30 faces to the left on the side of the groove towards the center of the casting. The presence of the smoke pipe passage 13 at the rear of the section and leading from the outer wall of the ring prevents the formation of such shoulders on the outer wall of the ring at the back. The presence of the flue 12 and clean-out opening 14 obviate corresponding immediate approaches to each other of the high and low flanges upon the forward half of each casting. 110

It will now be seen that when a top section as shown in Fig. 4 is turned upside down as in Fig. 5 over a bottom section 16 it will result in what was the right hand half of Fig. 4 becoming now the left hand half of the top section in its proper position as shown in Fig. 5 while the left hand half of the top section as shown in Fig. 4 will become the right hand portion of the top in its proper position as shown in Fig. 5. It will, therefore, be seen that these two castings have all the meeting edges of the walls with their high and low 120

125

130

flanges in such relative arrangement that the two sections of the radiator will fit together and that at each joint the high flanges will fit against low flanges and the low flanges fit against high flanges. In this way a so-called broken joint will be effected so that a rope or wick of asbestos or asbestos cement may be readily placed in the circular or oval opening made by the combining of the two 10 grooves.

It will also be seen that the arrangement of the high and low flanges is such as to prevent the upper section from sliding at all relative to the lower section from right to left or from left to right and is such as to prevent the upper section from sliding from front to rear or from rear to front more than the width of the groove.

Preferably the said arrangement of double flanges on the meeting edges of the two sections is carried out even upon the short outward extensions forming the clean-out opening 14 and the smoke pipe passage 13 as plainly indicated in Fig. 2. This further assures a completely gas-tight joint at both sides of each of these short passages.

Spaced about the meeting edges of each section there are provided the proper number of vertically apertured ears 37 so arranged that when two of the sections are assembled each ear of a section will register with an ear on the other section so as to receive therethrough a bolt 38. The several bolts and their nuts 39 in an obvious manner provide means to draw and hold all parts of the two sections together after the necessary packing 26 of asbestos rope or wick supplemented with cement has been placed in the cavity formed by the two grooves 25. These ears project outwardly from the walls of the dome 10 and flue 12 and from the outer wall of the ring 11 and inwardly from the inner wall of the ring.

Preferably the axis of the apertures in the ears 27 encroach somewhat into the general path of the groove 25 so as not to have the ears project too far from the casting. At these points however the grooves are enlarged or widened so as to provide a space all around the bolts 38 which space is filled 50 with the packing 26 to further assure a gas-tight joint at these places.

An enlargement or lug 40 is provided upon the outer end of the clean-out passage 14 at its right hand wall as seen in Fig. 2 and through this lug is provided a horizontal hole 31. A corresponding top section will accordingly provide a similar lug at the left-hand side of the clean-out passage as seen in Fig. 1. These apertured lugs afford a ready means for bolting a collar (not shown) to the completed radiator. A similar single lug 32 with a hole therethrough upon the left hand side of the smoke passage of the section as seen in Fig. 2 provides in the complete 65 two-section radiator a pair of similarly op-

positely arranged lugs to aid in securing a length of the smoke pipe thereto.

The top section 17 is exactly like the bottom section 16 except that the top has added thereto in the casting thereof the cap or top 70 21, being the part below the dotted line 4-4 in Fig. 4 and which part appears also in Figs. 1, 5 and 6. To one versed in the art of casting it will be seen that the addition of this cap for the top section can be readily made 75 by adding to the patterns used for the bottom section a simple separate or detachable part.

What I claim as new and desire to secure by Letters Patent is:

1. A two-piece furnace radiator, composed of two substantially similar hollow sections, the edges of the abutting walls of the two sections being similarly formed and being provided with two spaced flanges of unequal height with a groove therebetween, the opposite equal fractional parts of each section having the high and low flanges reversely disposed whereby when the parts are assembled the low flanges of each section meet the high flanges of the other section and double but offset joints are provided having at all parts a combined cavity therebetween to hold a rope-shaped packing between the sections.

2. A two-piece furnace radiator, composed of two substantially similar hollow sections, the edges of the abutting walls of the two sections being similarly formed and being provided with two spaced flanges of unequal height with a groove therebetween, the opposite halves of each section having the high and low flanges reversely disposed whereby when the parts are assembled the low flanges of each section meet the high flanges of the other section and double but offset joints are provided having at all parts a combined cavity therebetween to hold a rope-shaped packing between the sections.

3. A two-piece furnace radiator, composed of two substantially similar hollow sections, each section having U-shaped cavities facing similar cavities on the other section, the edges of the abutting walls of the two sections being similarly formed by and being provided with two spaced flanges of unequal height with a groove therebetween, the opposite equal fractional parts of each section having the high and low flanges reversely disposed whereby when the parts are assembled the low flanges of each section meet the high flanges of the other section and double but offset joints are provided having at all parts a combined cavity therebetween to hold a rope-shaped packing between the sections.

4. A two-piece furnace radiator composed of two substantially similar hollow sections, each section having U-shaped cavities facing similar cavities on the other section, the edges

of the abutting walls of the two sections being similarly formed and being provided with two spaced flanges of unequal height with a groove therebetween, the opposite halves of each section having the high and low flanges reversely disposed whereby when the parts are assembled the low flanges of each section meet the high flanges of the other section and double but offset joints are provided having at all parts a combined cavity therebetween to hold a rope-shaped packing between the sections.

5. A two-piece furnace radiator composed of two hollow, horizontally disposed sections which are similar in general construction, the edges of the abutting walls of the two sections being similarly formed and being provided with two spaced flanges of unequal height with a groove therebetween, the opposite equal fractional parts of each section having the high and low flanges reversely disposed whereby when the parts are assembled the low flanges of each section meet the high flanges of the other section and double but offset joints are provided having at all parts a combined cavity therebetween to hold a rope-shaped packing between the sections.

6. A two-piece furnace radiator composed of two hollow, horizontally disposed sections which are similar in general construction, the edges of the abutting walls of the two sections being similarly formed and being provided with two spaced flanges of unequal height with a groove therebetween, the opposite halves of each section having the high and low flanges reversely disposed whereby when the parts are assembled the low flanges of each section meet the high flanges of the other section and double but offset joints are provided having at all parts a combined cavity therebetween to hold a rope-shaped packing between the sections.

7. A two-piece furnace radiator, having a central hollow dome closed at its top and open at its bottom to communicate with the top of the feed section, a hollow ring spaced from the dome, a flue connecting the dome and the ring and a smoke outlet projecting outwardly from the ring, said radiator being composed of two horizontally disposed sections, which are similar in general construction, the edges of the abutting walls of the two sections being similarly formed and being provided with two spaced flanges of unequal height with a groove therebetween, the opposite halves of each section having the high and low flanges reversely disposed whereby when the parts are assembled the low flanges of each section meet the high flanges of the other section and double but offset joints are provided having at all parts a combined cavity therebetween to hold a rope-shaped packing between the sections.

8. A two-piece furnace radiator having a central hollow dome closed at its top and

open at its bottom to communicate with the top of the feed section, a hollow ring spaced from the dome, a flue connecting the dome and the ring and a smoke outlet projecting outwardly from the ring, said radiator being composed of two horizontally disposed sections, which are similar in general construction except that the top section has a closure forming the cap of the dome, the edges of the abutting walls of the two sections being similarly formed and being provided with two spaced flanges of unequal height with a groove therebetween, the opposite equal fractional parts of each section having the high and low flanges reversely disposed whereby when the parts are assembled with the top section inverted, the low flanges of each section meet the high flanges of the other section and double but offset joints are provided having at all parts a combined cavity therebetween to hold a rope-shaped packing between the sections.

9. A two-piece furnace radiator, having a central hollow dome closed at its top and open at its bottom to communicate with the top of the feed section, a hollow ring spaced from the dome, a flue connecting the dome and the ring and a smoke outlet projecting outwardly from the ring, said radiator being composed of two horizontally disposed sections, which are similar in general construction, the edges of the abutting walls of the two sections being similarly formed and being provided with two different joint-forming members at different levels, the opposite halves of each section having the said two different joint-forming members reversely disposed whereby when the parts are assembled different joint-forming members meet and double but offset joints are provided at all co-operating abutting edges.

10. A two-piece furnace radiator having a central hollow dome closed at its top and open at its bottom to communicate with the top of the feed section, a hollow ring spaced from the dome, a flue connecting the dome and the ring and a smoke outlet projecting outwardly from the ring, said radiator being composed of two horizontally disposed sections, which are similar in general construction except that the top section has a closure forming the cap of the dome, the edges of the abutting walls of the two sections being similarly formed and being provided with two different joint-forming members at different levels, the opposite halves of each section having the said two different joint-forming members reversely disposed whereby when the parts are assembled different joint-forming members meet and double but offset joints are provided at all co-operating abutting edges.

In witness whereof I have affixed my signature, this 25th day of March, 1925.

ALBERT WAGSTAFF.
